UNITED STATES PATENT OFFICE.

HENRY C. HARRISON, OF POTOMAC, MARYLAND.

CANAL-LOCK.

SPECIFICATION forming part of Letters Patent No. 446,708, dated February 17, 1891.

Application filed July 8, 1890. Serial No. 358,101. (No model.)

To all whom it may concern:

Be it known that I, HENRY C. HARRISON, a citizen of the United States, residing at Potomac, in the county of Montgomery, State of Maryland, have invented certain new and useful Improvements in Canal-Locks, of which the following is a specification, reference being had therein to the accompanying drawings.

10 This invention relates to certain new and useful improvements in canal-locks; and it has for its objects, among others, to provide an improved device of this character which shall be efficient in operation and wherein provision shall be made for ready repairs when necessary and for the prevention of clogging of the guideway for the gates.

15 I form the gates of sections flexibly connected together, so as to permit of their being wound up within a caisson, and yet when extended shall form a water-tight gate. I provide sluiceways in some or all of the gate-sections with means for manipulating the valves when desired. I provide automatically-falling gates to cover the guideways for the gates as the latter are drawn in, so as to prevent the accumulation of mud and other foreign substances on the screw or guideway. I provide movable bridges which serve as 20 guides for the upper ends of the gates proper, and also as a bridge to permit access to the sluice-valves when the gates are closed.

25 Other objects and advantages of the invention will hereinafter appear, and the novel features thereof will be specifically defined by the appended claims.

30 The invention is clearly illustrated in the accompanying drawings, which, with the letters of reference marked thereon, form a part 40 of this specification, and in which—

Figure 1 is a view illustrating my improvements with one side in rear elevation and the other in vertical section. Fig. 2 is a top plan of the same. Fig. 3 is a vertical cross-section 45 through one of the gates proper. Fig. 4 is a vertical cross-sectional detail through a gate, showing the valve for water-balancing the gate. Fig. 5 is a detail showing a section of the lower gate.

50 Like letters of reference indicate like parts throughout the several views.

Referring now to the details of the draw-

ings by letter, A designates a caisson or tower of suitable construction supported upon suitable foundation, there being one upon each 55 side of the canal or lock.

B is a vertical shaft supported in suitable bearings within the caisson and carrying at its lower end a beveled pinion B', which is stepped upon a suitable step or toe b, preferably of lignum-vitæ, secured within a suitable recess b', as shown to the right of Fig. 1. This beveled pinion is preferably arranged to ride upon roller-bearings a, as seen at the right of Fig. 1. As each side of the lock is 65 the counterpart of the other, a description of one will suffice for both:

At the lower end of the caisson is an upwardly-extending flange a', which serves as a 70 guide for the lower inner face of the gate, as seen at the right of Fig. 1. This flange may be a wheel fast upon and moving with the shaft B, and upon said shaft there are fast two other wheels B'; provided with lugs b², as seen best in Fig. 2, to which lugs the flexible 75 gates are secured.

Upon the upper end of the shaft B there is a beveled pinion b³, which meshes with a beveled pinion b⁴ on the shaft B', supported in suitable bearings and arranged to be actuated from any suitable source of power. (Not shown.) Rotation of this shaft will 80 rotate the shaft B, and consequently the pinion B'.

85 C are the gates proper, each consisting of a plurality of water-tight sections c, tapered vertically, as seen in Figs. 1 and 3, and each section composed, preferably, of boiler-iron stayed by inclined braces c', as shown in Figs. 1 and 3. These sections are hinged together 90 upon their adjacent rear faces by means of suitable hinges c², as seen in Figs. 1 and 2, and the inner edge of the inner section is pivotally connected with the lug b² of the wheels on shaft B, as shown at c³ in Fig. 2. 95 This inner section is also made tapering in the direction of the length, as seen in Fig. 2, so that when the gate is extended, as shown at the left of Fig. 2, the said tapered section will be tightly pressed into the outlet-aperture of the caisson and form a water-tight joint, as seen at the left of said Fig. 2. The 100 gates are tapered vertically, being larger at their base, where the greatest pressure is to

be sustained, as readily seen from the drawings. The gate-sections are formed upon their vertical edges one with a V-shaped or analogous projection C⁴ to engage a correspondingly-shaped recess C⁵ in the adjacent edge of the adjacent section, as clearly shown in Fig. 2, so that when the gate is extended, as seen at the left of Fig. 2, water-tight joints will be formed between the sections, and the pressure of the water thereon will only tend to more firmly bind them together, as will be readily understood.

The gates are provided in some or all of their sections with sluiceways C⁶, which are controlled by the valves C⁷, which are tapered, as shown in Fig. 3, and designed to move in suitable ways of guides, as seen in said figure, their movement being regulated by means of vertical rods D, provided at their upper ends with hand-wheels or other provisions d, by which they are turned, and the valves being designed when raised to be inclosed within the boxing or chamber d' in the gate.

The gates are opened and closed through the medium of the vertical shafts and the wheels thereon, to which the gates are attached.

The gates are guided at their lower ends in any suitable manner. I prefer, however, to guide them as shown in Figs. 1 and 2, wherein E is a nut fixed to the lower edge of the gate and adapted to work on the longitudinal screw F, which is held in suitable bearings and at its inner end carries a beveled pinion F', meshing with the pinion B', as seen best in Fig. 1 at the right. This serves to relieve the upper end of the shaft B of strain, but may be sometimes omitted without affecting the practical working of the device. When the screw is employed, it is arranged within a suitable tube or casing F², as seen in Fig. 3, the nut working through a slot in the upper end of said tube or casing. Anti-friction rollers f are also preferably provided to decrease the friction of the parts, said rollers moving upon the tracks or guides f', as seen in Fig. 3.

In order to water-balance the gates when desired, I provide the same at the lower edge of the sections with apertures g, controlled by the valve G, provided with valve-stems G', designed to extend upward within convenient reach of the operator.

In order to prevent access of water to the tube or casing F², I form said casing upon its rear side with a vertical extension F³, the inner face of which is provided with a substantially V-shaped projection f⁸, which engages and works in a correspondingly-shaped recess f' in the rear side of the gate-section, as seen in Fig. 3.

In order to prevent accumulation of mud, muck, &c., upon the screw or in the guide for the gates, I provide hinged lower gates H, which are hinged near their lower ends and arranged upon the upper side of the gates—that is, so as to close in the direction

of the pressure of the water, as seen in Fig. 3. These gates are formed in overlapping sections, as seen in Figs. 1, 2, and 5, so arranged that each section may move independent of the other. When the gates C are closed, these gates lie vertically, as shown in Fig. 3, against the said gates C; but as said gates are opened the pressure of the water against the gates H closes them down over the screw or the guideways for the gates, as seen in Fig. 1. The outer or first sections of the gates C are provided with a plow or nose-piece C⁸, adapted to enter beneath the sections of the gates H as the gates C are moved outward, and thus force them out or up, as will be readily understood. At the entrance of the caisson I provide a hinged gate I, which is moved outward by the gates C as they are opened and automatically closed by the pressure of the water to seal the caisson as the gates are closed, as seen in Fig. 2.

J are bridges hinged, as at j, to any suitable support or breastwork and designed to be elevated upon their pivots by means of cords or chains J', attached to their outer ends and connected with any suitable hoisting apparatus. (Not shown.) These bridges embrace the upper ends of the gates C and serve as guides therefor, as seen in Fig. 3. They are lowered into position while the gates are open, and the gates when closed are guided at their upper ends thereby, said bridges being provided with longitudinal central openings for the passage of the valve-stems D as the gates are closed. These bridges will be formed of any suitable material and form a walk to support the operator when he has occasion to operate the sluice-valves or serve as a foot-path across the canal.

The wheels upon the shaft B are skeleton wheels, as shown, so as to provide ready access to the parts for the purpose of repair, allowing of the ready separation of any two sections of the gate in case of damage thereto, and the whole contents of the caisson may be removed bodily, if desired.

Various modifications in details may be resorted to without departing from the spirit of or sacrificing the advantages of the invention.

What I claim is—

1. In a canal-lock, the combination, with a caisson, of a flexible gate adapted to be drawn within said caisson, substantially as specified.
2. In a canal-lock, the combination, with a caisson, of a hinged sectional gate adapted to be wound upon a shaft within said caisson, substantially as specified.
3. In a canal-lock, the combination, with a caisson, of a flexible gate composed of hinged interlocking sections adapted to be wound within said caisson, substantially as specified.
4. An improved lock-gate formed of hinged interlocking sections, substantially as shown and described.
5. In a canal-lock, the combination, with the

- caisson formed with tapered outlets, of a flexible gate having its inner section tapered to conform to the taper of said opening, substantially as specified.
- 5 6. In a canal-lock, the combination, with the caisson, of a flexible gate adapted to be wound therein and an automatically-closing gate to the entrance of the caisson, substantially as specified.
- 10 7. In a canal-lock, the combination, with the caisson and the movable gates, of the lower hinged gates, substantially as and for the purpose specified.
- 15 8. In a canal-lock, the combination, with the caisson and the movable gates and the guide for the lower end thereof, of the hinged gates adapted to automatically close the guideway as the gates are opened, substantially as specified.
- 20 9. In a canal-lock, the combination, with the caisson, the gates, and the guideway, of the hinged lower gate and the nose upon the movable gate, substantially as and for the purpose specified.
- 25 10. In a canal-lock, the combination, with the caisson and the movable gates, of the hinged lower gates in overlapping sections, substantially as specified.
- 30 11. In a canal-lock, the combination, with the caisson and the movable gates, of the lower hinged gates in overlapping independently-moving sections, substantially as specified.
- 35 12. In a canal-lock, the combination, with the caisson and the movable gates, of the lower hinged gates in overlapping independently-movable sections and the nose upon the forward end of the gate, substantially as specified.
- 40 13. In a canal-lock, the combination, with the caisson and the vertical shaft, of the wheels on said shaft and the flexible gate secured to said wheels, substantially as and for the purpose specified.
- 45 14. In a canal-lock, the combination, with the caisson, the vertical shaft, and the wheels thereon formed with lugs, of the gates in hinged interlocking sections, the inner one of which is pivotally connected to said lugs, substantially as specified.
- 50 15. In a canal-lock, the combination, with the caisson and the vertical shaft, of the wheels thereon, the gate, the horizontal screw, and connections between said shaft, screw, and gate, substantially as specified.
16. In a canal-lock, the combination, with the caisson, vertical shaft, and the wheels thereon, of the flexible gate connected with said wheels, the horizontal screw to which the gate is attached, and the beveled pinion on the screw and shaft, substantially as and for the purpose specified. 55
17. In a canal-lock, the combination, with the caisson, the vertical shaft, the flexible gate connected therewith, and the horizontal screw, of the nut secured to the gate and engaging the screw, and connections, substantially as described, between the shaft and screw, as and for the purpose specified. 65
18. In a canal-lock, the combination, with the caisson, vertical shaft, the wheels thereon, flexible gate pivotally connected with said wheel, and the screw, of the beveled pinion on the screw, beveled pinion on the shaft meshing therewith, and the nut secured to the lower edge of the gate and engaged by the screw, substantially as specified. 70
19. The combination, with the casing F^2 , having the vertical extension provided with inward projection, of the movable gate provided with corresponding depressions to engage said projection, substantially as and for the purpose specified. 80
20. The combination, with the gate and the nut secured thereto, of the casing, the screw arranged therein and engaging the nut, and the anti-friction rollers on the gate traveling on the upper face of the casing, substantially as described. 85
21. The combination, with the movable gate, of the pivoted bridge adapted to serve as a guide to the upper end of the gate, substantially as specified. 90
22. An improved lock-gate formed in hinged interlocking sections, some of which are provided with sluiceways controlled by adjustable valves. 95

In testimony whereof I affix my signature in presence of two witnesses.
